HIGH SPEED CHOPPER

Herbert I. Chambers and Albert W. Fischer, Pasadena, Calif., assignors, by mesne assignments, to Consolidated Electrodynamics Corporation, Pasadena, Calif., a corporation of California

Filed May 26, 1958, Ser. No. 737,923

8 Claims. (Cl. 200—90)

This invention relates to electromechanical devices for making and breaking electrical circuits, and more particularly, is concerned with a high speed device for making and breaking circuits which can be used as a relay or as a high speed chopper.

Magnetically operated switches take a variety of forms, such as relays for switching large currents in response to control signals of much smaller levels. Also, magnetically operated mechanical switches are used for chopping D.C. signals at the rate of an A.C. signal applied to the electromagnetic circuit. The relay-type of device may also be used for commutating or switching in a scanning manner for discrete periods of time. Whatever form the electromechanical switching device takes, its frequency of operation is limited by the relatively large mechanical mass required to provide suitable magnetic properties, and, in addition, is limited by the large equivalent electrical mass in the form of inductance of the electromagnetic circuit. By very careful design, both the mechanical and electrical mass of such relay devices have been reduced to improve performance, but reliable operation of such devices at frequencies as high as 1,000 cycles per second, for example, is not generally attainable.

The present invention is directed to an electromechanical switching device which may be used as a simple relay, or a chopper, and capable of operating reliably at frequencies of several thousand cycles and even higher. This is accomplished by reducing the mechanical mass to that of a single fine conductive wire, and by reducing the electrical equivalent mass by using a permanent magnetic field.

In brief, the relay apparatus of the present invention includes permanent magnet means defining an elongated magnetic flux gap. A flexible current-conductive element is supported in the gap, the supporting means including at least one resilient support at one end of the conductive element. Means is provided for passing a current through the conductive element for deflecting the conductive element laterally due to the interaction of the current in the magnetic field in the gap. The resilient support permits the element to deflect laterally by allowing the ends of the element to move closer together. Contact means is provided which is actuated by the lateral movement of the element in response to the current applied therethrough.

For a more complete understanding of the invention, reference should be had to the accompanying drawing, wherein:

Fig. 1 is an elevational view partly cut away, showing a circuit-breaking device according to one form of the present invention;

Fig. 2 is an end view of the form of the invention shown in Fig. 1;

Fig. 3 is a sectional view of a modified form of the present invention;

Fig. 4 is a sectional view taken substantially on the line 4—4 of Fig. 3; and

2

Fig. 5 is a sectional view taken substantially on the line 5—5 of Fig. 3.

Referring to the form of the invention as shown in Figs. 1 and 2, the numeral 10 indicates generally a frame 5 which is substantially channel-shaped, with the righthand upright member 12 extending considerably higher than the lefthand upright member 14. Mounted to the frame member 10 is a magnet block 16, which may be of Alnico magnet material. The block is secured to the frame member 10 by means of screws 18. The magnet block 16 extends between the two upright end portions 12 and 14 of the frame member 10.

A pair of pole pieces 20 and 22 are bolted on either side of the magnetic block 16, as by means of bolts 24 15 extending through the block 16. The pole pieces 20 and 22 project upwardly and extend the full length of the block 16 between the end portions 12 and 14 of the frame 10. The upper end of the pole pieces 20 and 22 respectively have inwardly projecting portions 26 and 27 20 which are tapered along their inner opposed edges to define an elongated magnetic gap 28. It will be apparent that the gap extends the full length of the pole pieces 20 and 22.

A fine conductive wire element 30 is secured at one 25 end to the upright portion 12 of the frame member 10. The wire element is supported at the other end by a cantilever spring 32 which is curved at its upper end as indicated at 34. The fine wire element is drawn across the curved upper end and anchored as by means of solder or 30 other suitable means at its end 36. The cantilever spring 32 extends downwardly to a point opposite the lower end of the frame 10 and is rigidly secured at the lower end by means of a screw 38 which clamps the cantilever spring 32 together with a set of contact elements, to be herein- 35 after described, between a plurality of insulating washers to the frame 10. Thus the cantilever spring 32 applies tension to the wire element 30, and at the same time supports it in position in the magnetic gap 28 formed by the pole pieces 26 and 27.

The contact assembly associated with the lower end of the cantilever spring 32 involves a pair of contacts 40 and 42 which are secured to the cantilever spring by an insulating cement as indicated at 44. Cooperating contacts 46 and 48 are supported on the ends of cantilever spring elements 50 and 52 respectively. The contacts 40 and 45 46 are normally closed, while the contacts 42 and 48 are normally open. Cantilever supporting springs 50 and 52 can be arranged to provide a make-before-break condition at the contacts if so desired. A plurality of insulating washers, as indicated at 54, clamp the cantilever 50 spring elements 32, 50, and 52 in conventional manner of multi-contact relays. Conductive leads 56 and 58 are provided for bringing out electrical connections to the contacts 40 and 42 respectively.

In operation, a potential is applied between the ends 55 of the fine wire element 30, as by connecting a potential source between the lower end of the cantilever spring 32 and the frame 10. The resulting current passing through the wire element 30 interacts with the magnetic field in the gap 28 to produce a lateral displacement of the wire element 30. This lateral displacement is in a vertical plane in the arrangement shown in Figs. 1 and 2.

Lateral displacement of the wire element 30 causes the ends thereof to move closer together. As a result, the cantilever spring support element 32 is caused to move to 65 the right so as to close the contacts 42 and 48 and to open the contacts 40 and 46. When the potential is withdrawn and the current ceases to flow in the wire element 30, the cantilever spring 32 returns to its initial position.

Thus it will be seen that the device of Figs. 1 and 2 70 may be used as a relay, the presence of a potential across the input causing contacts to open and contacts to close.

An alternating signal can be applied across the input if desired, causing the spring element 30 to vibrate at the frequency of the input signal. As a result, the contacts are caused to make and break at twice the frequency of the input signal, resulting in a high frequency chopper.

An alternative embodiment of the present invention is shown in Figs. 3, 4 and 5. In this arrangement, the frame of the device consists of an upper plate 60 and a lower plate 62, a pair of cylindrical members 64 and 66, and a central plate 68. The central plate 68 is clamped between the two cylindrical members 64 and 66, and the end plates 60 and 62 are clamped to the outer edges of the cylindrical members 64 and 66 by bolt members, such as indicated at 70, which are secured to the lower plate 62 and have nuts 72 which clamp against the upper end plate 60. Annular insulating spacers 74 and 76 are preferably provided between the upper and lower plates 60 and 62 and the cylindrical members 64 and 66 to insulate the plates electrically.

A conductive wire element 78 is anchored at either end respectively in the upper and lower plates 60 and 62. The wire element 78 is formed with crimped sections 80 to provide flexible tensioning of the wire element 78, or may have a tension spring similar to 32.

As best seen in Fig. 4, the central plate 68 is provided with a central opening 82 through which the wire element 78 passes. The central plate 68 is cut to form a pair of integral cantilever supported adjustable arms 84 and 86. Suitable screw means, such as indicated at 88, may be provided for bending the arms toward each other to provide an adjustment of the spacing between the outer ends of the cantilever arms 84 and 86.

The wire element 78 is immersed in a magnetic field formed by a pair of pole pieces positioned above and below the central plate 68, the pole pieces being indicated at 90 and 92. The pole faces are secured to blocks of magnetic material such as Alnico, as indicated at 94 and 96, the blocks having curved surfaces to fit against the inner surfaces of the cylindrical members 64 and 66. With the wire element immersed in a magnetic field, current passing through the magnetic element will cause it to deflect. The current may be connected by suitable leads connected to the end plates 60 and 62. These end plates are insulated from each other by virtue of the annular insulating rings 74 and 76 and by insulating bushings 98 through which the connecting bolts 70 pass.

Lateral movement of the wire element 78 in response to current passed therethrough is utilized to make and break contacts, the contacts being best shown in Fig. 4. One set of contacts comprises a spring wire 100 which is anchored in a hole 102 in the central plate by a suitable insulating cement. The wire 100 projects into the opening 82 in the central plate and is positioned to one side of the wire element 78. The wire contact element 100 is normally in contact with an associated stop 104 which is secured in an opening 106 in the adjustable cantilever arm 84 by suitable insulating cement.

Similarly, a wire contact element 103 is secured in a hole 110 in the central plate and projects into the opening 82 to the opposite side of the wire element 78 from the contact element 100. An associated stop element 112 is secured in an opening 114 in the cantilever arm 86.

The wire element 78 is provided with a small insulated contact 116 with a ribbon pigtail 117, the contact 116 engaging the wire contact elements 100 and 103. The pigtail 117 extends to an insulated support pin 119 for making an external electrical connection. In this manner, lateral displacement of the wire element 78 in two directions respectively closes the contacts 100 and 103 with contact 116. Screws 88 adjust the position of the stops 104 and 112 to vary the spacing between the contacts 100 and 103. Electrical connections are made to the pigtail 117 and the contact elements 100 and 103.

Sponge rubber damping pads 118 are preferably provided which are cemented into position and fill the space

between the contact elements 100 and 103 and the sides of the opening 82. These pads prevent bouncing or vibration of the contact elements 100 and 103.

The entire assembly is mounted inside a protective housing which is in two parts including an upper cup-shaped cover 120 and a base member 122. The base member and cover member are telescopically joined and brazed together at the joint to provide a hermetically sealed container. Electrical connecting pins 124 are provided in the base member 122, which extend through glass seals 126 for providing electrical connections to the element 78 and the contacts 100, 103, and 116. The wire connections have not been shown for the sake of clarity.

From the above description it will be seen that an electromechanical circuit breaking device has been provided which is capable of operating at high speeds. The device can be used as a relay or as a chopper. The mechanical inertia of the device is very small so that the moving mass as represented by the wire element is extremely small. The electrical equivalent inertia is very small because the inductance of the single wire conductor is of course extremely small. Because of the small inductive fields, the noise level is very low so that the device provides excellent switching performance.

What is claimed is:

1. A high speed switching device comprising a flexible current-conductive straight wire element, magnetic means defining an elongated magnetic gap, means for supporting the conductive element in the gap including a resilient support at one end of the element for maintaining tension on the wire element, the elongated magnetic gap extending substantially the full length of the flexible element, means for passing a current through the flexible element, the current producing a lateral deflection of the flexible element due to the interaction of the current and the magnetic field in the gap, the resilient support permitting the element to deflect laterally by allowing the ends of the element to move closer together, and contact means actuated by movement of the element in response to the current applied through the element, the contact means being electrically insulated from the flexible element to provide switching of an isolated circuit.

2. Apparatus as defined in claim 1 wherein said resilient support includes a cantilever spring to which the element is secured at one end, and the contact means includes contacts insulatedly supported by the cantilever spring and movable therewith and fixedly supported contacts positioned adjacent the moving contacts, whereby the contacts are brought in and out of engagement by movement of the flexible element in response to variations in the current passed therethrough.

3. Apparatus as defined in claim 2 further including a source of alternating current electrically connected across the flexible element for imparting a periodic movement to the flexible element and associated cantilever spring, whereby the contacts are periodically engaged to effect a chopper operation.

4. A high speed switching device comprising a flexible current-conductive wire element, magnetic means defining an elongated magnetic gap, means for supporting the conductive element in the gap under tension, the elongated magnetic gap extending substantially the full length of the flexible element, means for passing a current through the conductive element, the current producing a lateral deflection of the center of the conductive wire element due to the interaction of the current and the magnetic field in the gap, and contact means actuated by lateral movement of the wire element in response to the current applied through the element, the contact means being electrically insulated from the flexible element to provide switching of an isolated circuit.

5. Switching apparatus comprising a main frame including a pair of spaced plates, a wire element extending between said plates and resiliently supported therefrom,

a pair of contact elements positioned respectively on either side of the wire element, a contact sleeve insulatedly mounted on the wire element and adapted to engage the contact elements when the center region of the wire element is laterally displaced, means for resiliently supporting the contact elements from the main frame, a pair of adjustable stops normally engaging respectively each of the first pair of contacts for adjusting the spacing of the contacts, and magnetic means mounted on the main frame including pole pieces positioned on either side of the wire element for immersing the wire element in a magnetic field.

6. Switching apparatus comprising a main frame, a wire element resiliently supported by the frame, a pair of contact elements positioned respectively on either side of the wire element, a sleeve contact on the wire element adapted to engage the contact elements when the center region of the wire element is laterally displaced, means for resiliently supporting the contact elements from the main frame, a pair of stops normally engaging respectively each of the first pair of contacts, and magnetic means mounted on the main frame including pole pieces positioned on either side of the wire element for immersing the wire element in a magnetic field.

7. Switching apparatus comprising a main frame, a wire element resiliently supported by the frame, a pair of contact elements positioned respectively on either side of the wire element, means for resiliently supporting the contact elements from the main frame, whereby the contact elements are respectively movable with lateral movement in opposite directions of the wire element, a contact insulatedly secured to the wire element and movable

5

therewith, displacement of the last-named contact by the wire element moving the contact into and out of engagement with the first pair of contacts, and magnetic means mounted on the main frame including pole pieces positioned on either side of the wire element for immersing the wire element in a magnetic field.

8. Switching apparatus comprising a main frame, a wire element resiliently supported under tension by the frame, a pair of contact elements positioned respectively on either side of the wire element, means for resiliently supporting the contact elements from the main frame, a contact member secured to the wire element and engaging the contact elements, whereby the contact elements are respectively movable with lateral movement in opposite directions of the wire element, magnetic means providing a unidirectional magnetic field mounted on the main frame including pole pieces positioned on either side of the wire element for immersing the wire element in a constant magnetic field, and means for passing an alternating current through the wire element to cause the wire element to oscillate in the magnetic field.
